PAD FOR TOY TRAIN TRACKS

Charles S. Satterthwait, Kenilworth, Pa.

Application December 2, 1933, Serial No. 700,738

10 Claims. (Cl. 46—48)

This invention relates to pads for toy train tracks, and more particularly to the production of a device for supporting toy train tracks, which device will act both as a means to prevent injury to polished surfaces by vibration of the tracks upon the surfaces, and to prevent slipping of the tracks upon such surfaces.

It is well known to those familiar with the art and to possessors of toy trains in general, that the rapid movement of the train upon the tracks causes these tracks, or rather the metal supports or ties upon which the tracks are mounted, to vibrate upon any surface upon which they are placed. This vibration causes both abrasion of the surface and slipping of the tracks. Additionally, the metal supports coming into contact with the surface causes unpleasant noise. A further disadvantage of the toy train tracks as now constructed lies in the fact that the means for maintaining the track sections in connected relation comprises slip joints at adjacent ends of track sections, which slip joints after a brief period of use become loosened, permitting the track sections to separate as a result of vibration.

An important object of this invention is the provision of an article of manufacture which may be readily applied over the normal cross tie or support for toy train tracks, and which when applied thereover will afford an anti-slipping support for the tie, and at the same time deaden the sounds ordinarily resulting from operation of the train over the track, and which article likewise comprehends a means for connecting adjacent track sections to one another through such cross tie or supporting elements.

Other objects of the invention are the production of a device of this character which may be cheaply and readily manufactured, which will be durable in service, and which is readily applied.

These and other objects I attain by the construction shown in the accompanying drawing, wherein for the purpose of illustration, I have shown a preferred embodiment of my invention, and wherein

Figure 1 is a longitudinal sectional view through adjoining track units showing a connecting pad for use in connection therewith;

Fig. 2 is a similar sectional view through an intermediate section of the track, showing a pad for use with an intermediate tie element; and

Figs. 3 and 4 are perspective views of the pads shown in Figs. 1 and 2, detached.

Referring now more particularly to the draw-

ing, the numeral 10 generally designates the rail of a toy train track having a head usually in the form of a hollow bead indicated at 11. One end of this bead mounts a projecting tang 12 adapted to engage in the bead of the track 60 of an associated section and forms the sole means of connecting such sections to one another. The rails 10 are usually mounted on inverted channel-shaped cross tie elements indicated at 13 to which they are secured in any suitable manner, the arms 14 of this cross tie element having out-turned seating flanges 15 adapted to rest upon the surface upon which the track is laid. There are usually three cross tie elements 13 on each track section, one being disposed adjacent 70 each end of the section and one at the center of the section. Therefore, when two sections are coupled together at the coupling, two cross tie elements are arranged in close proximity to one another. The remaining or central cross 75 tie elements are well spaced from any of the other tie elements.

In accordance with my invention I provide pads such as shown at 16 and 17 in Figs. 3 and 4, these pads being formed of resilient rubber 80, and each comprising a base 18 and an up-standing marginal rim 19. The marginal rim defines an opening which is of a length equal to the length of the cross tie elements. The type shown in Figs. 1 and 3 which is intended 85 both as a cushioning and anti-skidding support and as a coupling for adjacent track sections has this opening of a width slightly less than the defines between the remote edges of the seating flanges 15 at opposite sides of cross tie 90 elements 13 on adjacent ends of connected track sections. By the term "opening" as here employed, the opening at the surface of the base element 18 is referred to, and preferably the marginal rim 18 at the longitudinal sides of the 95 base element has its inner wall sloping inwardly and upwardly as indicated at 20, so that when the pad is applied, the inner edges of the marginal rims will closely approximate the sides of the channel section of the tie element at their 100 upper ends.

When a pad of this type is applied to the tie elements at adjacent ends of connected track sections, due to the fact that the defines between the defining rim at the base is slightly 105 less than the defines between the remote edges of remote seating flanges of these elements, the pad will be placed under tension, and, accordingly, will take a slight curvature as indicated at 21 in Fig. 1. The tension not only causes this 110

curvature, but causes a constant resilient action, bringing the tracks into engagement with one another, so that a proper connection therebetween is constantly insured. The curvature 5 itself causes the longitudinal side edges of the bottom of the base to come into contact with any flat surfaces on which the track is disposed, so that the weight of the track is concentrated upon these edges. The pad being 10 of resilient rubber, and, therefore, of relatively high friction coefficient as compared with the metallic supports ordinarily employed, will of itself tend to prevent any shifting of the track and concentration of the weight on line contacts 15 by this curvature will accentuate the frictional engagement and render any movement by the relatively feeble vibrations set up by the train passing thereover extremely unlikely. Furthermore, since the weight is concentrated on relatively restricted resilient surfaces of live rubber, the vibration is in a large measure taken up by these surfaces with resultant lessening of any liability to movement and deadening of the sounds ordinarily attending operation.

20 25 The form of pad shown at 17 in Figs. 2 and 4 is for use with intermediate cross tie elements and is made of slightly less width as regards its opening than the width of the cross tie element at the outer edges of its seating flanges.

30 35 The construction and operation of this element otherwise corresponds exactly to that set forth above except, of course, there is no coupling function.

Since the construction illustrated is capable 35 of considerable modification without in any manner departing from the spirit of my invention, I do not wish to be understood as limiting myself thereto except as herein claimed.

I claim:

40 45 1. In combination with the cross tie element of a toy train track, a soft resilient base of friction material underlying the tie element, and means for detachably connecting said base and the tie element.

45 50 2. In combination with the cross tie element of a toy train track, a soft resilient base of friction material underlying the tie element, and means for detachably connecting said base and the tie element, the under surface of the element being arched.

55 60 3. In combination with the cross tie element of a toy train track, a soft resilient base of friction material underlying the tie element, and means for detachably connecting said base and the tie element, said attaching means co-acting with the cross tie to arch the under surface of the base.

4. The combination with adjacent ends of connected toy train track sections and a tie element underlying and secured to each section, of a soft resilient pad of friction material underlying both tie elements and having connection with said tie elements preventing separation thereof.

5. The combination with adjacent ends of connected toy train track sections and a tie element underlying and secured to each section, of a soft resilient pad of friction material underlying both tie elements and having connection with said tie elements preventing separation thereof, the under surface of the pad being arched.

6. The combination with adjacent ends of connected toy train track sections and a tie element underlying and secured to each section, of a soft resilient pad of friction material underlying both tie elements, and means at the sides of said pad engaging remote edges of said tie elements yieldably maintaining the track sections in connected relation through resilience of the pads.

7. The combination with adjacent ends of connected toy train track sections and a tie element underlying and secured to each section, of a soft resilient pad of friction material underlying both tie elements having flanges at its side edges to engage the remote side edges of the tie elements, said flanges being normally spaced apart a distance less than the distance between the side edges of the tie elements.

8. In combination with the cross tie element of a toy train track, a soft resilient base of friction material underlying the tie element, and means for detachably connecting said base and the tie element comprising flanges having upwardly and inwardly inclining inner faces.

9. In combination with the cross tie element of a toy train track, a soft resilient base of friction material underlying the tie element, and means for detachably connecting said base and the tie element comprising flanges at the sides of the pad adapted to engage the side faces of the tie element.

10. In combination with the cross tie element of a toy train track, a soft resilient base of friction material underlying the tie element, and means for detachably connecting said base and the tie element comprising flanges at the sides of the pad adapted to engage the side faces of the tie element, said flanges being normally spaced apart a distance less than the distance between the side edges of the tie element.

CHARLES S. SATTERTHWAIT.

Patent No. 1,969,279

Granted August 7, 1934

CHARLES S. SATTERTHWAIT

The above entitled patent was extended June 26, 1951, under the provisions of the Act of June 30, 1950, for 6 years and 234 days, from the expiration of the original term thereof.

Commissioner of Patents.
